UNITED STATES PATENT OFFICE.

CARL RASMUS FREDERIK HOMMEL AND REINHOLDT JOHAN HOMMEL, OF
FREDERIKSBERG, NEAR COPENHAGEN, DENMARK.

TROLLEY-POLE OF ELECTRIC TRAM-CARS OR THE LIKE.

SPECIFICATION forming part of Letters Patent No. 738,193, dated September 8, 1903.

Application filed January 15, 1903. Serial No. 139,205. (No model.)

To all whom it may concern:

Be it known that we, CARL RASMUS FREDERIK HOMMEL, shop superintendent, of 4 St. Knudsvej, and REINHOLDT JOHAN HOMMEL, engineer, of 9 Mathildevej, Frederiksberg, near Copenhagen, in the Kingdom of Denmark, have invented certain new and useful Improvements in Connection with the Trolley-Poles of Electric Tram-Cars or the Like; and we do hereby declare the following to be a full, clear, and exact description of the invention, such as will enable others skilled in the art to which it appertains to make and use the same, reference being had to the accompanying drawings, and to characters or figures of reference marked thereon, which form a part of this specification.

This invention relates to improvements in trolley-poles, and has for its object the provision of means to prevent the trolley-pole being forced upward when the contact-roller jumps off the line-wire, thereby preventing the free end of the pole from knocking against the line-wire stays or suspensions.

Arrangements for controlling the trolley-pole have been designed to act on the cord hanging from contact-roller and placed at the rear of the car. Such devices are uncertain in their action, and the way they are mounted on the car is inconvenient.

The device forming the subject-matter of this invention is mounted on top of the car and is directly connected to the trolley-pole and is so constructed that as soon as the contact has slipped off the wire the pole will be pulled down below the wire, thereby preventing it from striking the line-wire suspensions.

Referring to the drawings, in which like parts are similarly designated, Figure 1 is a side elevation of the device. Fig. 2 is a rear view of Fig. 1, and Figs. 3 to 7 are details.

A suitable base-plate 10 carries a fixed bolt *b*, on which is rotatable a sleeve *b*, to which sleeve is also pivoted at *a* the trolley-pole *a*. This pole is urged against the line-wire by any suitable or convenient device, which, however, does not form part of this invention.

Rigidly secured to the sleeve *b* is a pin *c*, having a reduced free end *c'* and provided with a groove 11 near the sleeve *b*. Over the grooved portion is fitted a sleeve *e*, having a

projection 12, in which is a hole 13 to retain one end of a coil-spring *d*. A set-screw 14, passing through the sleeve *e*, takes into the groove 11 and holds the sleeve in any desired angular position on the pin, thereby increasing or decreasing the tension of the spring *d*. The other end of the coil-spring is held in a hole *f* on a rock-arm *g*, that is mounted on the reduced end *c'* of the pin *c*. This arm *g* is forked and has between the forks a web *i*, and on one of the forks is formed a boss *h*, that fits inside the end of the coil *d* to support it. Pivoted in the forked end of the lever *g* at *q* is a pawl *p*, Figs. 5 and 6, having lateral projections *z*, on which take the noses *y*, one on each fork of the lever. The pawl *p* has secured to its shank an ear *u*, to which is connected one end of a rod *v*, whose other end passes through an eye *w*, rotatably mounted on the trolley-pole *a*, and carries a stop *x*, adjustable along the rod *v* above the eye *w*. A spring *r*, secured to the web *i*, urges the pawl *p* against a disk *t*, rigidly mounted on the reduced portion *c'* of the pin *c* and between the forks of lever *g*. This disk has two teeth—one, *s*, against which the pawl is nominally held, and one, 15, acting as a stop to limit the upward movement of lever *g* and against which the end of the web *i* strikes. On the end of the lever *g* is an ear *k*, to which the lower end of the rod *m* is pivoted, the upper end of this rod passing through a revolute eye *n* on the trolley-pole *a*, and below the eye *n* is a stop *o*, adjustable along the rod *m*.

The operation is as follows: When the contact-roller slips off the line-wire, the trolley-pole *a* is swung upward, the eye *w* striking the stop *x*, thereby tripping the pawl *p* and allowing the lever *g* to be urged upward by the coil-spring *d*. During the turning of the lever *g* the noses *y* engage the projections *z* on the pawl *p* and the two move as a unit around the pin *c*, thereby pulling down rod *v* and the trolley-pole *a*. This rotation will if the spring be sufficiently wound continue until the web *i* strikes the tooth 15. When the trolley-pole is pulled farther down by means of the usual cord, the eye *n* will strike the stop *o*, depress the lever *g*, rewind the spring, and simultaneously elevate the rod *v* and cause the pawl *p* to ride over the disk *t*.

Said pawl will then be forced to its seat when sufficiently rotated by the spring *r* to hold the lever *g* in normal position.

Having thus described our said invention, 5 what we claim as new therein, and desire to secure by Letters Patent, is—

1. The combination with a pivoted trolley-pole, of a lever connected with and rotatable transversely to the movement of said pole, 10 mechanism for locking the lever against rotation, and means actuated by the pole for releasing the locking mechanism, substantially as described.

2. The combination with a pivoted trolley-pole, of a lever connected therewith, mechanism for rotating the lever transversely to the movement of said pole, mechanism for locking the lever against rotation, means actuated by the pole for releasing the locking mechanism, 20 and means actuated by the lever for returning the lever to its locked position, substantially as described.

3. The combination with a trolley-pole, of a lever rotatable about a pin, a spring to rotate 25 the lever, a pawl to hold the lever in normal position, and a rod actuated by the trolley-pole when it slips off the line-wire to release said lever, to draw the trolley-pole down, substantially as described.

30 4. The combination with a trolley-pole, of a lever rotatable about a pin, a spring to rotate the lever, a pawl to hold the lever in normal position, means to release the pawl to allow the lever to be rotated by the spring, a stop 35 to limit the rotation of the lever, and means actuated by the depression of the trolley-pole to return the parts into normal position, substantially as described.

5. The combination with a bolt and a trolley 40 rotatable about the same, of a pin also rotatable about said bolt, a spiral spring on said pin, a lever rotatable on the end of the pin

by said spring, a pawl pivoted to said lever to hold it ready to operate, means actuated by the trolley-pole to trip the pawl to release 45 the lever, and means connected to the lever and operated by depressing the trolley-pole to return the parts to normal position, substantially as described.

6. The combination with a bolt and a trolley-pole rotatable about the same, of a substantially horizontal pin, a coil-spring thereon, a forked lever rotatable on the pin, a toothed disk fixed on said pin between the forks of the lever, a pawl pivoted to one end of the 50 lever and adapted to engage the disk, a rod pivoted to the pawl, an eye on the trolley-pole through which the rod passes and an adjustable stop on the rod above the eye, substantially as described.

7. The combination with a bolt and a trolley-pole rotatable about the same, of a substantially horizontal pin, a coil-spring thereon, a forked lever rotatable on the pin and having a web extending between the forks for a part 55 of their length, a disk having two teeth fixed on the pin between the forks of the lever, a spring-urged pawl pivoted at one end of the lever and normally engaging one tooth on the disk, a rod pivoted to the pawl, an eye on the trolley-pole through which said rod passes, a stop adjustable along the rod above the eye, a second rod pivoted to one end of the lever, a second eye on the trolley-pole, through which the second rod passes and a stop adjustable along the 70 rod below the eye, substantially as described.

In testimony that we claim the foregoing as our invention we have signed our names in presence of two subscribing witnesses.

CARL RASMUS FREDERIK HOMMEL.
REINHOLDT JOHAN HOMMEL.
